DESIGN FOR A SERVICE TRAY AND STAND NESTABLE UNIT

Will E. Wais, Chicago, Ill.

Application January 30, 1947, Serial No. 136,523

Term of patent 14 years

(Cl. D33—14)

To all whom it may concern:

Be it known that I, Will E. Wais, a citizen of the United States and a resident of Chicago, in the county of Cook and State of Illinois, have invented a new, original, and ornamental Design for a Service Tray and Stand Nestable Unit, of which the following is a specification, reference being had to the accompanying drawing, forming a part thereof, and in which:

Fig. 1 is a perspective view of a service tray and stand nestable unit, in nested condition, showing my new design;

Fig. 2 is a rear perspective view of the same;

Fig. 3 is a perspective view of a single nestable service tray and stand therefor.

I claim:

The ornamental design for a service tray and stand nestable unit, as shown and described.

WILL E. WAIS.
